[57] CLAIM

The ornamental design for a motorcycle fairing, substantially as shown and described.

DESCRIPTION

FIG. 1 is a front perspective view of a motorcycle fairing showing the new design;

FIG. 2 is a side elevation view of the fairing, as attached to a motorcycle, looking from the left;

FIG. 3 is a top plan view thereof;

FIG. 4 is a front elevation view thereof; and

FIG. 5 is a rear elevation view thereof.

The fragmentary broken line representations of portions of a motorcycle in FIGS. 2 and 3 and the broken line representation of a head light in FIGS. 1, 3 and 4 illustrate the environment in which the fairing is used but form no part of the design. The right side of the motorcycle fairing is a mirror image of FIG. 2.
